UNITED STATES PATENT OFFICE.

CHARLES H. HODGKINS, OF PITTSBURGH, PENNSYLVANIA, ASSIGNOR TO WESTINGHOUSE ELECTRIC & MANUFACTURING COMPANY, A CORPORATION OF PENNSYLVANIA.

SWITCH MECHANISM.

Application filed November 16, 1917. Serial No. 202,345.

To all whom it may concern:

Be it known that I, CHARLES H. HODGKINS, a subject of the King of Great Britain, and a resident of Pittsburgh, in the county of 5 Allegheny and State of Pennsylvania, have invented a new and useful Improvement in Switch Mechanisms, of which the following is a specification.

My invention relates to switch mechanisms and particularly to switch mechanisms having main switches and auxiliary switches controlled thereby.

One object of my invention is to provide a switch mechanism of the above-indicated 15 character that shall embody a main and an auxiliary switch which are combined in a simple and inexpensive manner, so that the auxiliary switch may be operated by the leakage flux of the main switch without interfering with the operation of the latter.

In many control systems, it is essential to provide main operating switches which effect the operation of interlock or auxiliary switches. The armature of the main switch 25 is mechanically associated with the auxiliary switch in a manner to effect operation of the auxiliary switch when the main switch is operated. However, the above method of operating the auxiliary switch is 30 impractical in many cases where the magnetic circuit which operates the main armature is of an insufficient capacity to perform the added work which would be necessary in order to operate the interlock switch.

35 In a switch mechanism constructed in accordance with my invention, the main switches are provided with means for governing the operation of the auxiliary switches by means of the leakage flux of the 40 main switches. An auxiliary switch, which is maintained in an open position by means of a spring mechanism, is associated with each main switch, and an armature, which is 45 operated by the leakage flux of the main switch, is provided for releasing the spring mechanism to permit the closing of the auxiliary switch.

In the accompanying drawing, Fig. 1 is a 50 sectional side elevational view of a switch mechanism constructed in accordance with my invention, and Fig. 2 is a front elevational view of the switch mechanism illustrated in Fig. 1.

Referring to the accompanying drawing, 55 a switch mechanism 1 embodies a main

switch 2 and an auxiliary or interlock switch 2^a, which is suitably mounted upon an insulating support 3. The main switch 2 embodies an energizing coil 4 which is mounted upon a core member 5, a pair of relatively 60 movable contact members 6 and 7 and an armature 8. The core 5 is secured to the insulating support 3 in any suitable manner, as by means of a bolt 9 which serves another function to be set forth hereinafter. The 65 armature 8 is pivotally mounted upon a frame 10, which is composed of magnetizable material and is provided with a projection 11 which engages a lug 12 on the frame for limiting the movement of the armature. 70 The contact member 6 is mounted upon a support 13, and the contact member 7 is pivotally mounted, in any suitable manner, upon the armature 8.

The auxiliary switch 2^a embodies an arm 75 14 which is pivotally mounted on a support 15 and is provided with a contact member 16 for bridging the contact terminals 17 and 18. A post 19, which is secured to the insulating support 3 in any suitable manner, 80 projects through the arm 14 and is provided with an enlarged head 20 near one end thereof. A spring 21 is disposed around the post 19 intermediate the arm 14 and the head 20 in a manner to tend to close the auxiliary 85 switch. A pin 22, which projects through the insulating support 3 and engages the arm 14, is provided with a collar 23, and, intermediate the collar 23 and the insulating support 3, is located a coil spring 24 which 90 is adapted to overcome the action of spring 21 and maintain the auxiliary switch 2^a in an open position, under certain conditions. An auxiliary armature 25, which is pivotally mounted intermediate its ends on a support 26, is pivotally connected, near one end, to the pin 22, and the other end thereof is adapted to co-operate with the bolt 9 of magnetizable material which secures the core 95 5 to the insulating support 3.

Assuming the apparatus to be in the position illustrated in the drawing, the coil 4 may be energized to attract the armature 8 and complete a magnetic circuit for the coil through the core 5, the frame 10 and the armature 8. When the above magnetic circuit is completed and the switch 2 is closed, a sufficient amount of leakage flux is produced for attracting the auxiliary armature 25 to the extension 9 of the core 5. As soon 105 110

as the armature 25 is operated and the spring 24 is compressed thereby, the spring 21 becomes operative to effect the closing of the auxiliary switch 1.

5 If so desired, the air gap between the armature 25 and the bolt 9 may be varied in order to adjust the time of operation of the armature 25. A bolt 30, which is mounted on the armature 25, may be provided to 10 effect such adjustment.

Modifications in the apparatus and arrangement and location of parts may be made within the spirit and scope of my invention and such modifications are intended 15 to be covered by the appended claims.

I claim as my invention:

1. The combination with a member biased 20 in one direction and means for normally preventing the operation of said member in said direction, of an electromagnet and means controlled by the leakage flux of said electromagnet for rendering said preventing means inoperative.

2. The combination with an electromagnet, 25 of a switch having a spring mechanism associated therewith for maintaining the same in an open position under predetermined conditions, an armature operated by the leakage flux of said electromagnet for 30 permitting operation of the spring mechanism when operated and means for closing said switch.

3. In a switch mechanism, the combination 35 with a main switch comprising a coil, a core and an armature for completing a magnetic circuit through said core and for operating the main switch contacts, and an auxiliary armature operated by the leakage

flux of the main switch, of an auxiliary switch, means for closing the auxiliary 40 switch, and a spring mechanism for maintaining the auxiliary switch in an open position, said spring mechanism being compressed by the auxiliary armature to permit the closing of the auxiliary switch. 45

4. In a switch mechanism, the combination with an electrically-operated main switch and an auxiliary armature operated by the leakage flux of the main switch, of an auxiliary switch, means for maintaining 50 the auxiliary switch in an open position which is opposed by the auxiliary armature and means for closing the auxiliary switch.

5. The combination with an electromagnet having an energized core member 55 mounted upon an insulating support and an armature member therefor, of a magnetizable member detachably mounted in said core member and through said support, and an armature member adapted to be attracted 60 by said magnetizable member.

6. The combination with an insulating support, of a pair of switches and an electromagnet for actuating one of said switches mounted upon one side of said support, a 65 magnetizable member magnetically connected to said electromagnet extending through said support, and an armature member having a pole piece for co-operating with said magnetizable member 70 mounted upon the other side of said support and controlling said other switch.

In testimony whereof, I have hereunto subscribed my name this 1st day of November, 1917.

CHARLES H. HODGKINS.
